EXTRACTION OF DRYING OIL

Robert F. Ruthruff and Donald F. Wilcock, Chicago, Ill., assignors to The Sherwin-Williams Company, Cleveland, Ohio, a corporation of Ohio

Application April 10, 1941, Serial No. 387,846

26 Claims. (Cl. 260—428.5)

The present invention relates to the recovery or treatment of natural and artificial drying oils such as fish oil, linseed oil, soya bean oil, dehydrated castor oil, cottonseed oil, tung oil, and many other oils, to provide a fraction thereof having improved drying or other qualities.

Vegetable and animal drying oils comprise generally a mixture of triglycerides of saturated and unsaturated higher fatty acids in mixed or single acid glyceride form with or without free fatty acids. The common fatty acid components of the glycerides of the better known vegetable oils are stearic, oleic, linoleic and linolenic acids. Animal oil glycerides contain in addition higher fatty acid components. Only the unsaturated fatty acid components contribute drying quality, particularly those derived from linoleic and linolenic acids. The capacity for drying is represented by an analytically determined "iodine number." The iodine number is higher, the greater the degree of unsaturation, which in general induces more rapid drying and harder oil films.

The invention may be applied to drying oils already isolated, or it may be applied to materials containing drying oils, such as cotton seed meal, soya bean meal, and other sources of such oils, or material impregnated with such oils. Since the invention depends upon the use of materials which are complete solvents for oil when used in adequate amounts for a given temperature, or selective solvents when used in limited amounts, or at a lower temperature, it is immaterial to the invention whether an isolated oil or an oil-impregnated material, or an oil solution is the originally available material.

The preferred aspect of the invention is the treatment of isolated oils. Since the drying oils are most useful in their drying nature, for paints, varnishes and the like, the invention is described with particular emphasis on securing oil fractions of improved drying quality. However, those skilled in the art will readily perceive that the operations may be performed and varied in order better to attain other specific objectives.

Linseed oil is naturally a satisfactory drying oil, yet its drying capacity may be increased by a suitable fractionation. Soya bean oil gives limited satisfaction as a drying oil, having naturally a lower iodine number than linseed oil. Its drying capacity may be increased by suitable fractionation. Many uses of soya bean oil do not require drying properties. Although its increasing availability at reasonable costs makes it desirable for drying-oil uses, yet in 1939 only 7.5% of the production was so used. The present invention is

especially useful to fractionate soya bean oil into a fraction of increased iodine number, and a fraction of decreased iodine number. Given a low cost process for fractionation, the raw oil may be split for its drying and non-drying fields of use, with advantage in the drying field, and with or without advantage in the non-drying field. In the latter field, sometimes the drying quality is disadvantageous.

10 Since the invention is particularly adaptable in its economic aspects, pecuniary and national, for treating soya bean oil, it is herein described and illustrated with reference to soya bean oil, without being limited thereto.

15 In the concern for fractionating vegetable drying oil, a practice well established in the petroleum field has been turned to. It is well known to treat petroleum oil with a selective solvent capable of forming two liquid phases under chosen conditions for that end. Thus, the paraffinic-rich oils and the aromatic-and-naphthenic-rich oils have been concentrated in the two liquid phases. This has been practiced with lubricating oil distillate. The process is known generally as solvent extraction. It produces as one liquid phase, the "extract" which is largely the solvent with an extracted content representing the more aromatic and naphthenic components of the original oil; and as the second liquid phase the "raffinate" which is the more paraffinic components of the oil containing a small dissolved content of the solvent. Solvent is distilled away from the two separated phases.

20 Numerous solvents have been so used with vegetable and animal drying oils, and extract and raffinate fractions obtained having respectively increased and decreased iodine numbers, indicating theoretically in the former case improved drying qualities. However, in actual performance such extract fractions of higher iodine number have been inferior to the original untreated oil, taking a much longer time to dry.

25 A like unexpected result has been that the raffinate fractions of lower iodine number dried much quicker than the original oil. Based on the iodine numbers, these are entirely unexpected results. These results have presented a problem solved by means of the present invention.

30 It is therefore an object of the present invention to treat a drying oil, or a source or other material containing drying oil, to a solvent and to treat the solution to secure a fraction of the original oil.

35 It is a particular object of the invention to

treat a furfural solution containing drying oil to a selective oil-extracting solvent.

It is also an object of the present invention to recover from drying oils a fraction which has an iodine number increased over the iodine number of the original oil, and a shorter drying period than the original oil.

Corollary objectives are to produce a fraction of drying oil which has less capacity for drying, and to provide a raffinate drying oil which has either a lengthened or a shortened drying time in comparison with the original oil.

It is another object of the invention to produce a drying oil having less than the natural proportion of anti-oxidants to oil.

A particular object of the invention is to secure a soya bean source oil having improved drying characteristics compared to the natural soya bean oil.

Various other and ancillary objects and advantages of the invention will become apparent from the following description and explanation of the invention, which is given in connection with the accompanying drawings in which:

Fig. 1 represents a number of graphs showing data pertaining to the treatment or extraction of soya bean oil with furfural at 20° C.

Fig. 2 is a diagrammatic representation of the preferred process of extracting drying oil with furfural, extracting the furfural extract with hydrocarbon, recovering two fractions of oil, and recovering the hydrocarbon and the furfural.

Fig. 3 is a diagrammatic arrangement of process and apparatus for carrying out the preferred process of Fig. 2, in a continuous manner.

Fig. 4 is a diagrammatic representation of modifications of the process as set forth in Fig. 2, the dotted lines of the figure representing a portion of Fig. 2, to which the said modifications apply.

It has heretofore been suggested that drying oils may be improved in drying qualities by selective solvent extraction with a furan compound, such as furfural. Attempts to use furfural at normal temperatures for such purpose have been successful to split the oil into a fraction of higher iodine number, and a fraction of lower iodine number than that exhibited by the oil charged. The procedure in general is as follows:

The oil is thoroughly brought into contact with furfural in proportion to permit a separation into two liquid phases at a desired temperature. Furfural in the extract and in the raffinate is distilled off, and the resulting oils analyse with higher iodine number from the extract and lower iodine number from the raffinate. But these are respectively worse and better than the original oil in time of drying.

By investigation, it was determined that the furfural also extracts certain substances natural to the oil, and herein referred to as "anti-oxidants," along with the high-iodine number extract oil, leaving the raffinate oil deficient in anti-oxidants. This clearly explained the unexpected differences in drying times of the two oils resulting from the solvent extraction treatment.

The anti-oxidants natural to the oil are believed to include at least certain phosphatides, which includes so-called lecithin in the case of soy bean oil. The so-called lecithin is a well known anti-oxidant. The present invention is not concerned with the constitution of the anti-oxidants, and whatever they are, they are referred to by source and function, for example, as natural anti-oxidants.

A study of the drying times of oil fractions has shown that furfural is highly selective of the natural anti-oxidants, and so much so, that a very light extraction with furfural, that is, using a low ratio of furfural to oil, will remove a major portion of them, while extracting but a very minor part of the oil. This has been determined by finding that such a light extraction, leaving the raffinate oil substantially unchanged in amount and in iodine number, compared to the charge, greatly reduces the drying time of the raffinate oil compared to the charged oil.

Therefore, it is one aspect of the invention that the drying oil may be given a light extraction with furfural to extract the natural anti-oxidants selectively, with little extraction of oil.

Attempts were made to operate a process by first giving such a light extraction with furfural, then an effective oil-splitting extraction with furfural, and distillation of the furfural from the extract and the raffinate. The oil thus obtained from the raffinate was expectedly quicker-drying than the natural oil, yet it had a lowered iodine number. However, surprisingly, the oil obtained from the extract was slower-drying than the natural oil, yet having a higher iodine number, in spite of the fact that substantially all of the natural antioxidants were removed from the original oil in the first and light extraction with furfural. This presented a further problem of shortening the drying time of the extract-oil over that of the charged oil, whereby the extract oil could be improved in drying time as well as in capacity.

Further investigation taught that the process employed was creating anti-oxidant material from the furfural. It was observed that upon distillation of the furfural extract fraction, by direct heat under a vacuum, or by direct heat while introducing steam, the oil became colored, and the more colored the oil, the slower its drying time. It was determined that there is formation of a black tar or gum in thus distilling the furfural extract. Either such product or an accompanying product exercised an anti-oxidant action on the extract oil residue of distillation. Thus, the simple application of the petroleum oil technique, using furfural on drying oil, worked disadvantages in effecting the presence in the oil fraction having high-iodine number, of natural and formed anti-oxidants.

The invention is further related to modification of the process to avoid the presence of these anti-oxidants. In doing this, the natural anti-oxidants may be disposed of by the light-extraction as above set forth. The formed anti-oxidants may be avoided in the extract oil, either by removal or by the prevention of their formation. Where removal is employed, the natural anti-oxidants need not be removed by the light furfural extraction, but may be retained for removal with the formed anti-oxidants. When the formation of anti-oxidants is avoided, the natural anti-oxidants may or may not be removed by a selective extraction, according to the process employed to avoid the formation of the anti-oxidants resulting from a distillation of furfural from the extract phase.

Removal of anti-oxidants from the extract oil may be effected by a physical process such as contact with an adsorbent, such as activated charcoal, adsorbent clay, active magnesia, "Magnesol," tricalcium phosphate, or contact with a solution, such as of sodium bisulfite, or a light extraction with a limited volume of furfural. The term "Magnesol" is a trade name of a prod-

uct sold by the Westvaco Chlorine Products Corporation, of New York city, New York, of which product the active material is a synthetic magnesium silicate. All of these remove both kinds of anti-oxidants, except that the sodium bisulfite solution removes only formed-anti-oxidants.

Prevention of the formation of anti-oxidants from furfural may be effected by chilling the furfural extract to a point where two liquid phases result, the extract being high in furfural which has high affinity for any natural anti-oxidants. Residual furfural in the raffinate of this chilling may be distilled off with little if any amount of anti-oxidant formation. This procedure involves low yield of extract oil for the processing and material required.

A second method, which is partially effective, is to dilute the furfural extractant of the process with an agent which forms a mixed solvent of substantially the same extracting value. Such a mixture is one having 60 volumes of furfural and 40 volumes of acetone. The extract is distilled, but there being less furfural, less anti-oxidant is formed. In other words, prevention is effected by reducing the amount of furfural involved in proportion to extract oil recovered.

A third method which is the preferred one, is to extract the furfural extract with an appropriate solvent which is selective of the extract oil while being sufficiently immiscible with the furfural and poorly selective for any natural anti-oxidants dissolved in the furfural. Further, such solvent should be one which is distillable from the extract oil without forming anti-oxidant. The paraffinic hydrocarbons in liquid form are such solvent. Suitable ones are propane, the butanes, petroleum ether (largely pentanes and hexanes), n-heptane, higher hydrocarbons, and "VMP" naphtha, which includes such higher hydrocarbons. The latter is the most efficient in the preferred process. One important feature resides in the degree to which the hydrocarbon extraction is carried out. A severe extraction removes both natural anti-oxidants and oil from the furfural extract, and a light extraction removes oil selectively leaving anti-oxidants. Thus, a hydrocarbon extraction may be carried out lightly in the presence of furfural to retain the anti-oxidants in the furfural, or exhaustively to remove the anti-oxidants from the furfural. A light extraction which leaves in the furfural the anti-oxidants also leaves a small amount of some high-iodine number oil. In a cyclic process the light extraction is carried out to secure the improved drying oil, and an exhaustive extraction is carried out to produce a residual oil with its natural anti-oxidants for non-drying uses of the oil. Thus, the process is operable to split a drying oil containing natural anti-oxidants, into a fraction of higher-iodine number and lowered-to-no anti-oxidant content, and a fraction with the residual oil and the residual or all of the anti-oxidant content, or in another variation little or none of the anti-oxidants.

Accordingly, the preferred process of the present invention is a plural solvent extraction process. The raw drying oil may be optionally freed of natural anti-oxidants by a light extraction with furfural. As given in detail below, this is omitted in the preferred practice. The natural oil, with its anti-oxidants is then to be split by solvent extraction with furfural to produce furfural extract and raffinate. The furfural extract is given a light extraction with liquid paraffin hydrocarbon, selectively to remove some oil content

into a hydrocarbon extract, which is distilled to remove the hydrocarbon and yield the improved quicker-drying higher iodine-number drying oil. The raffinate of the furfural extraction and the residual furfural phase of the hydrocarbon extraction (containing anti-oxidants and a slight amount of a high-iodine number oil) are combined and subjected to an exhaustive hydrocarbon extraction. This removes substantially all oil and anti-oxidants in a hydrocarbon solution, leaving a furfural phase which, with or without purifying distillation, may be reused.

If the original oil is lightly extracted with furfural to remove natural anti-oxidants, then selectively extracted to provide furfural extract and raffinate, then the hydrocarbon extraction is effected exhaustively, thus to secure all the oil.

The preferred process as above described may be carried out batchwise, or in continuous extracting and tower-distilling equipment common in the petroleum industry for like process steps. The selection of proportions of materials and the extent to which any step may be carried, are largely matters of judgement, based on conditions, equipment, degree of separation desired, and degree of improvement in drying time desired. The following information pertains to such operation.

Since drying oils vary in their specific composition, and in their response to solvent extraction at different temperatures, it is not possible to give data for various oils at all temperatures. However, this is readily obtainable by simple determination. The following discussion is pertinent to extraction with furfural of natural soya bean oil at normal temperatures in the vicinity of 20° C. This temperature has been chosen for the preferred operation of the process for soya bean oil to avoid special heating and chilling in the extraction process.

Fig. 1 is a plot of data obtained by extracting soya bean oil with various proportions by volume of furfural to oil at normal temperature. The oil and solvent are well mixed and allowed to separate in two liquid phases. Each phase is distilled to secure the oil content, and each oil specimen is analysed for its iodine number. The original oil has an iodine number of 131.5 (Wijs method).

Axis 10 represents the volumes of furfural to volumes of oil. Axis 11 shows the iodine number. Axis 12 shows a percentage in the lower or extract layer, as indicated by legends. The dotted line 13 represents the amount of the furfural taken up by the oil before phase separation is possible. This line 13 moves to the right with increasing temperature.

Curve 15 is a plot of the iodine numbers of oil extracted by the furfural when used in the amounts indicated along the axis 10, with the legend "Iodine number of extracted oil."

Curve 16 is a plot of the iodine numbers of the unextracted or raffinate oil when furfural is used in the amounts indicated along axis 10, with the legend "Iodine number of raffinate oil."

Curve 17 represents the percent of "phase separation," that is, percent by volume of the oil plus furfural taken, found in the lower or extract layer.

Curve 18 represents the percent by volume of the original oil which is in the extract.

Reading the graphs at the point 4 on axis 10, it is indicated that with 4 volumes of furfural to 1 volume of oil, 20% of the oil is extracted, 80% of the total extraction mass is the liquid extract phase, and 20% is the raffinate phase. The ex-

tract oil has an iodine number of 143, or 11.5 points above the raw oil; and the raffinate oil has an iodine number of 128.6, or 2.9 points below the original oil.

The graphs further show that the maximum iodine number is attained using 1 to 2 volumes of furfural to 1 volume of oil, with from 5% to 10% by volume or weight of the oil extracted. The extraction of oil high iodine number remains selective for much greater use of furfural with increased yield of extract, as shown by the continued higher location of curve 15.

DRYING TIME

The oils have been tested for drying time by a procedure which delays drying comparably, in order to accentuate the data for comparison. 6 cc. of oil, to which a standard drier is added is mixed with 5 gms. of ferrite yellow pigment. The latter is a retarder of drying, especially in the earlier stages of the drying action. The paste is spread on a plate in a uniform film by a doctor blade, and exposed to standard, or to the same, conditions where comparisons are made. The plate is weighed at frequent intervals and the weight plotted against time. The time required for increase in weight to begin is well known as the "induction period" (herein called A). The total time, called B herein, to attain a maximum weight is the time required to form a hard dry film. By calling the A-time for raw oil "Ao," a simultaneous comparison of A for a fraction obtained from a raw oil and the Ao of the raw oil itself, as a ratio of A to Ao, gives a significant value D used herein.

Table 1 represents a comparison of drying values of soya bean extract and raffinate oil obtained at the point 1.5 on the axis 10 of Fig. 1, and of the original charge of oil.

Table 1

Oil	Iodine No.	Induction period A, hours	Drying time B, hours	Ratio D
Raw oil.....	131.5	3	35	1.0
Extract oil.....	144.3	216	250	72.0
Raffinate oil.....	130.5	0	28	0.0

Table 1 shows clearly that the extract oil of highest iodine number takes longer to dry than the original oil and also the raffinate oil; and that the raffinate oil dries quicker than the raw oil, in spite of its having lost the more drying components. As stated heretofore, these facts result from removal of natural anti-oxidants from the raffinate oil, and placing them with formed anti-oxidants into the extract oil.

HYDROCARBON EXTRACTION

1 volume of soya bean oil having an iodine number of 130.4, and an induction period A of 73 hours, was extracted with 8 volumes of furfural. The extract oil was about 42% of the original charged oil. The extract oil had an iodine number of 140.4 while the raffinate oil had an iodine number of 123.3. The extract phase was divided into two parts, and extracted with petroleum ether and VMP naphtha, at about 20° C., respectively. About 1 volume of hydrocarbon to 3 volumes of extract phase was used. This is about 25.8 volumes of solvent (naphtha plus furfural) to 1 volume of extract oil. In the respective hydrocarbon extractions 84% and 87% of the extract oil was removed into the hydrocarbon phase. Oil of high iodine number remains in the

residual furfural phase. However, it may be extracted by further treatment with hydrocarbon solvent. Where a first hydrocarbon-extraction removed oil of 140.2 iodine number, the second hydrocarbon-extraction removed oil with iodine number of 155.3. But this oil, for reasons already given, is rich in natural anti-oxidants.

In the above two parallel hydrocarbon extractions, the results are closely identical, as shown in Table 2.

Table 2

	Hydrocarbon used on furfural extract				
	Petroleum ether B. P. 35°-55° C.		VPM naphtha		
	Iodine No.	A-period	Iodine No.	A-period	
20	Hydrocarbon extract oil.....	138	0.8	138.6	0.8
	Hydrocarbon raffinate oil.....	144	.....	147.7	.....

From the foregoing table, and the data on the original oil, it is seen that the first extraction with furfural removes 42% of the original oil. The second extraction, with hydrocarbon, removes from this roughly 85% or 36% of the original oil, as useful quick-drying oil, comparable as follows with the raw oil:

Table 3

	Yield, percent	Iodine number	Comparable	Drying D of new to raw
			induction period A in hours	
35	100	130.4	73	.....
40	36	138 to 138.6	0.8	0.01

PROCEDURE

Fig. 2 represents diagrammatically the relation of steps, whether conducted batchwise or in a continuous process. Block 20 represents a natural drying oil containing a fraction of higher iodine number (indicated as I+), a fraction of lower iodine number (indicated as I-), and natural anti-oxidants (indicated as AO). Block 21 indicates the step of lightly extracting the oil of block 20 with a solvent selective of the anti-oxidants AO, using such a small amount of solvent that an inappreciable amount of oil is extracted. Suitable solvents are furfural, the described 60-40 furfural-acetone, and others. The preferred solvent is furfural because that amount dissolved by the oil does not effect a mixture of the solvent so used with the furfural which is used in a subsequent step. Such a light extraction provides a furfural extract 22 containing the anti-oxidants AO. As indicated by the broken lines 23 and 24 to and from block 21, this extraction 21 is optional and preferably omitted, where it is permissible to provide the final fraction of oil having lowered iodine number with an anti-oxidant content for non-drying uses.

The line 25 leading from block 20 to block 26 indicates the preferred subjection of the oil of block 20 to a furfural (from supply 27) extraction 26, which of course, may also be practiced on the raffinate from the light extraction 21.

The extraction 26 is carried out with an amount of furfural which will yield two liquid phases 28 and 29 at a suitable separating temperature. The oil and furfural, as for example in a proportion

chosen from a data-chart such as Fig. 1, may be mixed at the separating temperature to effect an extraction, or be mixed at a higher temperature, and then cooled to a temperature at which a desired proportion of liquid phases, indicated by blocks 28 and 29, is effected.

The liquid phase 28 is represented by legends in block 28 indicating that it is the furfural (F) extract, with oil of higher iodine number (I+), and with anti-oxidants (AO) where the preferred path 20—25—26 is followed. The liquid phase 29 is the raffinate phase indicated as containing a small amount (f) of furfural dissolved therein, and oil of lowered iodine number (I-).

Paraffin hydrocarbon solvent liquid (from supply 30) is used for a light extraction indicated by block 31, of the extract phase 28, giving a hydrocarbon extract phase 32 and a raffinate phase 33. The extract phase 32 contains hydrocarbon (HC) and the desired oil of high iodine number (I+). Since the hydrocarbon predominates, it may be reduced in quantity or all removed by a distillation in still 34, yielding hydrocarbon 35 to be returned to supply 30, and the desired fraction 36 of high-iodine number oil with less than, or substantially free from its natural proportion of natural anti-oxidants, according to the exact manner selected to perform the steps to this point. The retention of hydrocarbon with drying oil permits use of such a mixture in some formulations.

The raffinate phase 33 of the light hydrocarbon extraction 31 contains largely furfural (F), natural anti-oxidants (AO), and a small amount of oil of high iodine number (I+). This raffinate 33 is combined with the raffinate 29 of the furfural extraction 26, to give combined raffinates indicated at 38, containing the oil of lower iodine number (I-) of block 29, furfural, and anti-oxidants. Although a small amount of oil of high iodine number (I+) is mixed with this, the resultant oil mixture is still oil of lower iodine number (I-) because it is all the oil remaining after removal of the oil (I+) of block 36.

The combined raffinates are extracted at 40 exhaustively with paraffin hydrocarbon liquid, as from the supply 30, giving an extract phase 41 and a raffinate phase 42, which is furfural. This may be returned to supply 27, or redistilled at 43 and then returned to said supply. The extract phase 41 predominates in hydrocarbon, and carries oil of lower iodine number (I-), that small quantity of oil of high iodine number which is found in raffinate 33 of the light hydrocarbon extraction, and anti-oxidants (AO) of said raffinate 33. This extract 41 may be distilled at 44 to remove some or all of the hydrocarbon as distillate 45, returnable to supply 30, and yield the oil fraction 46 having iodine number below that of the original oil 20, in association with natural anti-oxidants in greater than natural proportion, and preferably substantially all of the anti-oxidants of the original oil 20.

CONTINUOUS PROCESS AND APPARATUS

Fig. 3 represents apparatus for continuously carrying out the preferred process of Fig. 2 described above, as it has been applied to soya bean oil. The process employs a furfural supply 50, a naphtha supply 51, a multi-stage furfural extracting tower 52, a single-stage naphtha extracting tower 53, a multi-stage naphtha extracting tower 54, a first naphtha flash tower 55, and a second naphtha flash tower 56, with connecting pipes and valves indicated only by lines, all functioning as follows:

Raw oil from supply 58, is led by connection 59 into the lower end of tower 52, into the upper end of which line 60 brings furfural from supply 50. These liquid streams tend to flow away from their points of introduction toward the respective opposite ends of the tower, whereby they thoroughly mix and effect the extraction desired. Thus, furfural extract gathers at the bottom of tower 52, from which it is drawn off in line 61 to the upper end of tower 53. Also, raffinate oil gathers at the top of tower 52, from which it is drawn off in line 62 to the upper end of tower 54.

Naphtha for the light extraction is drawn from supply 51 by line 63 to the lower end of tower 53, wherein it flows against the furfural extract introduced in the upper end by line 61. Thus, the top and bottom of tower 53 provide respectively naphtha extract drawn off in line 64, and a raffinate furfural drawn off in line 65. Lines 64 and 65 lead respectively to the first naphtha still tower 55, and to the upper end of tower 54, where combining of the raffinate with raffinate material from line 62 is effected.

Naphtha for the exhaustive hydrocarbon extraction is drawn from supply 51 by line 63—66 to enter the lower end of tower 54, wherein it flows against the combined raffinates of the furfural and light naphtha extractions. The raffinate which results from this is furfural, drawn from the bottom of tower 54 and led by line 67 to the furfural supply 50. The hydrocarbon extract is led from the top of tower 54 by line 68, to the second naphtha still tower 56. From the two naphtha stills 55 and 56, naphtha distillate is returned to the supply 51 by the respective lines 70 and 71.

From the first naphtha still 55 the residue of oil having high-iodine number is drawn off at the bottom as indicated at 72. From the second naphtha still 56, the residue of oil having low iodine number and anti-oxidants, is drawn off, as indicated at 73.

In order to point out the materials of the same character, in Figs. 2 and 3, the following Table 4 is given, in which the number given is the designating character or line connection.

Table 4

	Material, or composition or process	Fig. 2	Fig. 3
50	Raw oil	20	58
	Furfural extraction	26	52
	Furfural extract	28	61
	Furfural raffinate	29	62
55	Light hydrocarbon extraction	31	53
	Hydrocarbon extract	32	64
	Hydrocarbon raffinate	33	65
	Exhaustive hydrocarbon extraction	40	54
	Hydrocarbon extract	41	68
	Hydrocarbon raffinate (furfural)	42	67
60	Oil—high iodine number	36	72
	Oil—low iodine number plus anti-oxidants	46	73

From the foregoing it will be appreciated that the invention has a broader aspect than the limited procedures above given for the preferred process and the preferred objectives. The invention is based in part upon the discovery that the liquid paraffin hydrocarbons have a selective action, when used in limited quantity, to extract oil selectively from a furfural solution of drying oil and natural anti-oxidants of drying oil. Although such solutions are described above as made preferably by selectively extracting drying oil with furfural, it is to be understood that the whole oil may be dissolved in furfural, which has a high affinity for the anti-oxidants. Since the liquid paraffin hydrocarbon may be used to

select oil from furfural solution and to leave anti-oxidants dissolved in furfural, it is readily understandable that it is possible to extract oil from such solution faster than anti-oxidants can be extracted. Thus, it is possible to produce a fraction of oil, regardless of its iodine number, which has less than the natural proportion of anti-oxidants to oil. For example, raw oil may be dissolved in furfural, then extracted selectively with paraffin hydrocarbon liquid, short of the point of completion where the anti-oxidants in the extract have the natural proportion of anti-oxidants to oil in the extract.

The process is subject to a number of variations to secure the improved drying oil of either low or high iodine number, with less than the natural proportion of anti-oxidants to oil, or substantially none at all. These variations are represented in Fig. 4, the dotted lines being used to show the portion carried over from Fig. 2, with reference to which the modifications are illustrated. The numbers applied to Fig. 2 and the legends are carried over into Fig. 4. The heavy lines of Fig. 4 represent various modifications, and it is to be understood that these include independent variations, all included in one diagram for convenience. The principles employed having been disclosed, each variation will be clearly understood by reference to the chart.

MODIFICATION NO. 1

In the light hydrocarbon extraction 31, the raffinate furfural 33 may be split into two portions designated 80 and 81. Each contains largely furfural (F), anti-oxidants (AO), and a small amount of oil (I+). One portion 81 is mixed (line 82) with the raffinate 29, at 38, for the processing as in Fig. 2. The portion 81 alternatively may be processed in any other way, as indicated by line 83. The portion 80 is returned (line 84) to the furfural extraction 26, thus increasing the proportion of anti-oxidants to oil involved in said extraction, but also increasing to a small extent the oil of high iodine number present in raffinate 33 as taken into portion 80. This amounts to using in extraction 26 some furfural containing dissolved anti-oxidants, which is permitted by reason of the high selectivity of furfural for them.

MODIFICATION NO. 2

The first hydrocarbon raffinate furfural 33 is not mixed at 38 with the furfural raffinate 29 at 38, but rather is disposed of separately at 85, thus to keep the anti-oxidant content of the material 33 away from the oil (I-) of the raffinate 29, when exhaustively extracted with hydrocarbon at 40.

MODIFICATION NO. 3

The furfural-extract oil 28, containing anti-oxidants may be taken along line 86 and exhaustively extracted at 87 with paraffin hydrocarbon liquid, whereby there are obtained a hydrocarbon extract 88, and a raffinate furfural 89. The extract 88 contains the oil (I+) and anti-oxidants (AO) dissolved in hydrocarbon. The extract is passed over solid adsorbent, such as activated charcoal, adsorbent clay, activated magnesia, "Magnesol," tricalcium phosphate, and like materials, which remove large amounts of anti-oxidant and but a small amount of oil. The adsorption step is indicated at 90, giving solid residue 91, and useful hydrocarbon solution 92 of oil (I+). This may be reduced in hydrocar-

bon content, as in still 93 to give a concentrate 94 of oil (I+), and recovered hydrocarbon 95.

MODIFICATION NO. 4

5 The above described exhaustive extraction 87 with hydrocarbon, may be practiced on the raffinate furfural 33, as shown by lead line 97, connecting such raffinate 33 and extraction 87. Thus, the oil (I+) in furfural extract 28, is divided into the oil (I+) of block 32, and oil (I+) recovered at 94. These may be combined in the hydrocarbon solution stage, as indicated by line 98, or elsewhere, or not combined at all.

MODIFICATION NO. 5

The furfural extract 28 is treated, as by direct, vacuum or steam distillation, represented by block 100, to remove furfural 102, and yield a residue 103 of oil (I+) with anti-oxidants (AO) present in the furfural extract 28. These will be natural anti-oxidants, and according to the method of removal, may include formed anti-oxidants. The residue 103 is then extracted lightly with furfural at 105, selectively to remove anti-oxidants and a small amount of oil, as a light furfural extract 110, leaving a raffinate phase 106, containing oil (I+) and a small amount of dissolved furfural (f). This amount (f) is so small that it can safely be distilled off at 107 without danger from too much formed anti-oxidants, to give oil (I+) as shown at 108, and recovered furfural 109. The extract phase 110 is rich in anti-oxidants (AO) and poor in oil (I+).

In this modification, the removal 100 of furfural (F) may be so incomplete that two phases result, one of which is furfural dissolving the anti-oxidants, whereby the said light furfural extraction 105 is effected by this incompleteness of removal of furfural.

MODIFICATION NO. 6

It is of course to be understood that in all these modifications, the step 21 (a light selective extraction for anti-oxidants) may be practiced, whereby the anti-oxidants present are materially reduced in proportion to oil to be treated.

LINSEED OIL

50 Although the invention has its preferred application to those drying oils which are of lower iodine number than linseed oil, it is to be understood that linseed oil may be improved by securing fractions thereof according to the invention herein described. The fractions may be either higher or lower in iodine number than the original linseed oil, and in either fraction the natural proportions of anti-oxidants to oil may be reduced or removed. Thus a fraction may be improved by (1) added capacity to dry, (2) by shorter drying time, or (3) both.

A linseed oil is used having an iodine number of 175.1, an induction period A of 18 hours, and a drying time B of 39 hours. It was extracted 65 according to step 26 (Fig. 2), with a ratio of 6.6 volumes of furfural to 1 volume of oil at 19° C. In the furfural extract was found 56.2% of the original oil. The extract phase was divided into three parts, each differently treated as follows:

70 Part 1.—The extract was stripped of furfural by vacuum distillation, followed and completed by use of fire heat and steam. The residue of oil had an iodine number of 185.9, and an induction period A of 51 hours. This shows the presence of anti-oxidants, which as it will appear

later, are largely those from the furfural distillation.

Part 2.—The extract was extracted at 19° C. with 0.09 volume of VMP naphtha to 1 volume of extract, with 49% by volume of the oil content going into the naphtha extract phase. This oil had an iodine number of 177.2, an induction period A of 1.1 hours and a drying time B of 13.5 hours. The oil is but slightly better in capacity to dry than the original oil, but improved greatly in its drying time. This fraction represents about 27% by volume of the original oil.

Part 3.—The extract was extracted at 19° C. with 0.22 volume of VMP naphtha to 1 volume of extract, with 76% by volume of the oil content going into the naphtha extract phase. This oil has an iodine number of 183.9, an induction period A of 1.5 hours, and a drying time B of 15 hours. The oil is better in both capacity to dry and in drying time, than the original oil. It represents a fraction of about 43% by volume of the original oil.

The oil in raffinates of the above extractions have properties as follows:

	Extraction by—		
	Furfural	Naphtha, part 2	Naphtha, part 3
Iodine No.....	161.2	194.2	192.3
Induction period A..... hours.....	7	—	—
Drying time B..... do.....	27	—	—

The improved drying time of the furfural raffinate, shows that natural anti-oxidants were taken out of the oil, into the furfural extract. The naphtha extracts the oil selectively from the furfural extract, leaving the natural anti-oxidants in the raffinate furfural. The part 3 above is a relatively more exhaustive extraction than part 2, and this is reflected in the apparent extraction of more natural anti-oxidants by the increased drying periods of the extract oil of part 3 over that of part 2.

The invention may be carried out in numerous ways within the scope of the appended claims.

We claim:

1. The method of treating drying oil to secure a fraction therefrom having a higher iodine number which comprises extracting the drying oil with sufficient furfural to provide a liquid furfural extract phase and a liquid raffinate oil phase, extracting oil from the said extract phase with a paraffin hydrocarbon solvent to form a residual furfural raffinate phase and a hydrocarbon extract phase containing oil of said higher iodine number, and reducing the hydrocarbon content of said phase to secure said fraction while lowering the proportion of said hydrocarbon to oil, whereby the distillation of furfural in the presence of oil is avoided, with the avoidance of forming anti-oxidants in the oil.

2. The method of treating natural drying oil containing natural anti-oxidants to secure a fraction therefrom having a higher iodine number and a shorter drying time than the untreated oil which comprises extracting the drying oil with sufficient furfural to provide a liquid furfural extract phase which contains the natural anti-oxidants of the oil and to provide a liquid raffinate oil phase, incompletely extracting oil from the said extract phase with a paraffin hydrocarbon solvent to form a residual furfural raffinate phase containing anti-oxidants and some oil and a hy-

drocarbon extract phase containing oil of said higher iodine number and free from its natural proportion of said anti-oxidants, and reducing the hydrocarbon content of said phase to secure said fraction while lowering the proportion of said hydrocarbon to oil.

3. The method of treating natural drying oil containing natural anti-oxidants to secure a fraction therefrom having a higher iodine number and a shorter drying time than the untreated oil which comprises lightly extracting the oil with furfural to leave substantially all the oil and to remove substantially all the anti-oxidants natural to the oil, again extracting the drying oil with sufficient furfural to provide a liquid furfural extract phase containing an appreciable fraction of the oil having higher iodine number than the original oil and a liquid raffinate oil phase, extracting the said extract phase with a paraffin hydrocarbon solvent to form a residual furfural phase and a hydrocarbon phase containing oil of said higher iodine number substantially free of natural anti-oxidants, and reducing the hydrocarbon content of said last phase to secure said fraction.

4. The method of claim 1 in which natural drying oil is employed containing natural anti-oxidants and in which the said furfural extraction is preceded by a relatively lighter extraction with furfural whereby anti-oxidants enter the earlier liquid furfural phase.

5. The method of treating drying oil to split it into two fractions having iodine numbers relatively higher and lower than the untreated oil and with the oil of higher iodine number having a shorter drying time than the original oil, which comprises extracting the drying oil with sufficient furfural to provide a liquid furfural extract phase and a liquid raffinate oil phase, lightly extracting the said extract phase with a paraffin hydrocarbon solvent to form a residual furfural phase retaining some oil and a hydrocarbon phase containing said quicker-drying oil of higher iodine number, removing hydrocarbon from said phase to secure the first of said desired oil fractions, combining the raffinate oil phase and the said residual furfural phase, exhaustively extracting the oil in said combined phases with a paraffin hydrocarbon solvent whereby to form a furfural phase and a hydrocarbon phase containing oil of lowered iodine-number, and removing hydrocarbon from said last mentioned phase to secure the second of said desired oil fractions.

6. The method of claim 5 in which natural drying oil is employed containing natural anti-oxidants, whereby said anti-oxidants enter the furfural extract and remain with the furfural phase of the first hydrocarbon extraction and then enter the hydrocarbon phase of the second hydrocarbon extraction, whereby they appear in the oil fraction having an iodine number below that of the original oil.

7. The method of claim 5 in which drying oil is employed from which natural anti-oxidants have been removed.

8. The method of claim 5 in which natural drying oil is employed containing natural anti-oxidants in which the said furfural extraction is preceded by a relatively lighter extraction with furfural whereby anti-oxidants enter the first liquid furfural phase.

9. The method of treating drying oil containing natural anti-oxidants to secure a fraction therefrom having a higher iodine number and a less proportion of natural anti-oxidants than the

untreated oil, which comprises lightly extracting the oil with furfural to remove anti-oxidants into a relatively small volume of furfural extract and leave a large volume of raffinate oil, extracting the said raffinate oil with sufficient furfural to provide a second liquid furfural extract containing desired oil of higher iodine number, and extracting all of said oil from said second furfural extract with a paraffin hydrocarbon liquid to secure a hydrocarbon solution of said desired fraction.

10. The method of treating drying oil to remove therefrom a fraction of higher iodine number, which comprises moving in intimate contact with each other counter-current streams of drying oil and of furfural whereby to extract into the furfural a fraction of the oil and to provide a stream of furfural extract, moving in intimate contact with each other counter-current streams of said furfural extract and of paraffin hydrocarbon liquid to provide a stream of furfural retaining oil and to provide a stream of hydrocarbon solution of said oil of said higher iodine number, and removing hydrocarbon from said hydrocarbon solution to secure an oil concentrate having a higher iodine number than the original oil.

11. The method of treating drying oil having natural anti-oxidants to secure a fraction therefrom having a higher iodine number which comprises moving in intimate contact with each other counter-current streams of drying oil and of furfural whereby to extract into the furfural a fraction of the oil and to provide a stream of furfural extract, moving in intimate contact with each other counter-current streams of said furfural extract and of paraffin hydrocarbon liquid to provide a stream of hydrocarbon solution of extracted oil of said higher iodine number and to provide a stream of furfural containing the remainder of said oil of the furfural extract and the natural anti-oxidants of the original oil, and removing hydrocarbon from said hydrocarbon solution to secure an oil concentrate having a higher iodine number than the original oil.

12. The method of treating drying oil having natural anti-oxidants to split it into two fractions having iodine numbers relatively higher and lower than the untreated oil and with the oil of higher iodine number having a shorter drying time than the original oil, which comprises moving in intimate contact with each other counter-current streams of drying oil and of furfural whereby to extract into the furfural a fraction of the oil and to provide a stream of furfural extract, moving in intimate contact with each other counter-current streams of said furfural extract and of paraffin hydrocarbon liquid whereby to extract a portion of the oil into said hydrocarbon to provide a stream of hydrocarbon solution of extracted oil having said higher iodine number and to provide a stream of furfural containing the remainder of said oil and the natural anti-oxidants of the original oil, removing hydrocarbon from said hydrocarbon solution to secure an oil concentrate having a higher iodine number than the original oil and less than the natural proportion of anti-oxidants to oil, combining the raffinate streams of the first and second counter-current actions, moving the combined stream of the said raffinates and a stream of paraffin hydrocarbon liquid in intimate contact with each other in counter-current relation exhaustively to remove extract oil into hydrocarbon solution and to remove attendant anti-oxidants into hy-

drocarbon solution in providing a stream of said hydrocarbon solution, and removing hydrocarbon from said solution whereby to secure an oil concentrate having an iodine number lower than the original oil and containing greater than the natural proportion of anti-oxidants to oil.

13. The method of treating drying oil containing natural anti-oxidants, which comprises dissolving said oil in furfural, and extracting a portion of the dissolved oil in said furfural by treatment with a paraffin hydrocarbon liquid to form two liquid phases, one being a hydrocarbon solution of oil, and the other being a furfural solution of oil and anti-oxidants, said portion of oil so extracted being such that any natural anti-oxidants extracted from the furfural solution with said portion are less in proportion to the said portion than in the original drying oil, and removing hydrocarbon from said hydrocarbon solution to secure an oil concentrate having less than the natural proportion of anti-oxidants to oil.

14. The method of treating drying oil to secure a fraction thereof, which comprises extracting the drying oil with sufficient furfural to provide a liquid furfural extract phase and a liquid raffinate phase, exhaustively extracting the furfural extract phase with a paraffin hydrocarbon liquid solvent to provide a liquid hydrocarbon extract phase containing oil and to provide a raffinate furfural phase, and removing hydrocarbon from said hydrocarbon extract phase to secure an oil concentrate having an iodine number greater than that of the original oil.

15. The method of treating drying oil to secure a fraction thereof, which comprises extracting the drying oil with sufficient furfural to provide a liquid furfural extract phase and a liquid raffinate phase, and extracting the raffinate phase with a paraffin hydrocarbon liquid solvent to provide a liquid hydrocarbon extract phase containing oil and to provide a raffinate furfural phase.

16. The method of treating drying oil to secure a fraction thereof, which comprises extracting the drying oil with sufficient furfural to provide a liquid furfural extract phase and a liquid raffinate phase, and exhaustively extracting the raffinate phase with a paraffin hydrocarbon liquid solvent to provide a liquid hydrocarbon extract phase containing oil and to provide a raffinate furfural phase.

17. The method of treating drying oil containing natural anti-oxidants to secure a fraction thereof, which comprises extracting the drying oil with sufficient furfural to provide a liquid furfural extract phase and a liquid raffinate phase, exhaustively extracting the furfural extract phase with a paraffin hydrocarbon liquid solvent to provide a liquid hydrocarbon extract phase containing oil and to provide a raffinate furfural phase, and subjecting said hydrocarbon extract phase to the action of a solid adsorbent whereby to adsorb anti-oxidant material from the hydrocarbon solution of the oil.

18. The method of treating drying oil to secure a fraction thereof, which comprises extracting the drying oil with sufficient furfural to provide a liquid furfural extract phase and a liquid raffinate phase, extracting the furfural extract phase lightly with a paraffin hydrocarbon liquid while selecting a lower proportion of anti-oxidants to extracted oil than characterizes the original oil to provide a liquid hydrocarbon extract phase containing oil and to provide a raffinate furfural phase containing oil and natural

anti-oxidants, splitting the raffinate furfural phase into two portions, mixing one portion with an additional quantity of said original drying oil and using said mixture with additional furfural to provide a second furfural extract phase and a second liquid raffinate phase.

19. The method of treating drying oil to secure a fraction thereof, which comprises extracting the drying oil with sufficient furfural to provide a liquid furfural extract phase and a liquid raffinate phase, whereby the furfural phase contains oil of iodine number higher than that of the original oil, extracting the furfural extract phase with a paraffin hydrocarbon liquid solvent to provide a hydrocarbon extract having a portion of oil having an iodine number greater than that of the original oil, whereby said portion is substantially free from furfural, and removing hydrocarbon from said hydrocarbon extract phase to provide an oil concentrate having an iodine number greater than that of the original oil.

20. The method of treating drying oil containing natural anti-oxidants which comprises treating it with a quantity of organic liquid incompletely miscible with it, which liquid is a solvent for the anti-oxidants and a selective solvent for a fraction of the oil having a higher iodine number than the original oil, whereby to provide a liquid extract phase containing anti-oxidants and said fraction both dissolved in said organic liquid, and to provide a raffinate phase containing a second fraction of oil having an iodine number lower than that of the original oil, extracting a portion of the dissolved oil in said liquid extract phase by treatment with a paraffin hydrocarbon liquid to form two liquid phases, one being a hydrocarbon solution containing said portion of oil, and the other being a solution of oil and anti-oxidants in said organic liquid, said portion of oil so extracted being such that any natural anti-oxidants extracted from the said liquid extract phase with said portion are less in proportion to said portion than the proportion in the original oil of natural anti-oxidants to oil, and removing hydrocarbon from said hydrocarbon solution to secure an oil concentrate having less than the natural proportion of anti-oxidants to oil.

21. The method of treating drying oil containing natural anti-oxidants which comprises lightly and incompletely extracting the oil with a small quantity of organic liquid which is a solvent for natural anti-oxidants and a selective solvent for a fraction of the oil having a higher iodine number than the original oil, whereby to provide a liquid extract phase containing a small fraction of the original oil and anti-oxidants both dissolved in said organic liquid, and to provide a raffinate phase containing a large proportion of the original oil as a second fraction having a lower iodine number than the original oil, the quantity of organic liquid being such as to provide said second fraction of oil as one having a lower iodine number, a less drying time, and a less induction period than the original oil.

22. The method of treating drying oil containing natural anti-oxidants which comprises lightly and incompletely extracting the oil with a small quantity of organic liquid which is a solvent for natural anti-oxidants and a selective solvent for a fraction of the oil having a higher iodine number than the original oil, whereby to provide a liquid extract phase containing a small fraction of the original oil and anti-oxidants both dissolved in said organic liquid, and to provide a

raffinate phase containing a large proportion of the original oil as a second fraction having a lower iodine number than the original oil, the quantity of organic liquid being such as to provide said second fraction of oil as one having a lower iodine number, and a less drying time than the original oil, and a substantially zero-time induction period in terms of hours.

23. The method of treating drying oil containing natural anti-oxidants which comprises lightly and incompletely extracting the oil with a small quantity of an organic liquid predominating in furfural content, which liquid is a solvent for said anti-oxidants and a selective solvent for a fraction of the oil having a higher iodine number than the original oil, whereby to provide a liquid extract phase containing a small fraction of the original oil and anti-oxidants both dissolved in said organic liquid, and to provide a raffinate phase containing a large proportion of the original oil as a second fraction having a lower iodine number than the original oil, the quantity of organic liquid being such as to provide said second fraction of oil as one having a lower iodine number, a less drying time, and a less induction period than the original oil.

24. The method of treating drying oil containing anti-oxidants which comprises lightly and incompletely extracting the oil with a small quantity of furfural, whereby to provide a liquid furfural extract phase containing a dissolved small fraction of the original oil having an iodine number greater than that of the original oil and containing dissolved anti-oxidants, and to provide a raffinate phase containing a large proportion of the original oil as a second fraction having a lower iodine number than the original oil, the quantity of furfural being such as to provide said second fraction of oil as one having a lower iodine number, a less drying time, and a less induction period than the original oil.

25. The method of treating drying oil containing natural anti-oxidants which comprises lightly and incompletely extracting the oil with a small quantity of furfural, whereby to provide a liquid furfural extract phase containing a dissolved small fraction of the original oil having an iodine number greater than that of the original oil and containing dissolved anti-oxidants, and to provide a raffinate phase containing a large proportion of the original oil as a second fraction having a lower iodine number than the original oil, the quantity of furfural being such as to provide said second fraction of oil as one having a lower iodine number, a less drying time, and a less induction period than the original oil.

26. The method of treating natural drying oil containing natural anti-oxidants which comprises lightly extracting the oil with a small quantity of furfural to leave substantially all the oil and to remove substantially all the anti-oxidants natural to the oil, whereby to secure one fraction comprising a solution in furfural of a small amount of oil of higher iodine number than the original oil and substantially all the anti-oxidants of the original oil, and a second fraction comprising the remainder of the oil with an iodine number lower than that of the original oil with furfural dissolved therein, said second fraction being substantially free from natural anti-oxidants.
